(57) **CLAIM**

The ornamental design for a robotic vacuum cleaner, as shown and described.

DESCRIPTION

1. Robotic vacuum cleaner

FIG. 1.1 is a front view of a robotic vacuum cleaners according to a first embodiment;

FIG. 1.2 is a rear view;

FIG. 1.3 is a left view;

FIG. 1.4 is a right view;

FIG. 1.5 is a top view;

FIG. 1.6 is a bottom view; and

FIG. 1.7 is a perspective view.

The broken lines shown are included for the purpose of illustrating portions of the robotic vacuum cleaner which form no part of the claimed design.

1 Claim, 7 Drawing Sheets
